UNITED STATES PATENT OFFICE.

CLYDE P. ROSS, OF CHICAGO, ILLINOIS, ASSIGNOR TO ROBERTS AND SCHAEFER COMPANY, OF CHICAGO, ILLINOIS, A CORPORATION OF ILLINOIS.

HOIST.

Application filed September 23, 1926. Serial No. 137,269.

This invention relates to a hoisting apparatus. The form illustrated herewith is particularly adapted for use in handling coal or cinders in connection with railroads, although it is not limited to that use. One object of the invention is to provide a simple and compact device wherein a tipping bucket may be moved into and out of and above a receiving bucket, and may be so moved along two or more inclines of different degrees of inclination. Another object is to provide in connection with such apparatus means whereby such bucket may be moved and held at all times in upright position without the necessity of complicated supporting mechanisms and without the use of rigid bails or additional moving parts. Other objects will appear from time to time throughout the specification and claims.

My invention is illustrated more or less diagrammatically in the accompanying drawings, wherein:

Figure 1 is an elevation with parts in section showing the device installed in connection with a railroad;

Figure 2 is a section on an enlarged scale showing in greater detail the pit and bucket of Figure 1;

Figure 3 is a detailed perspective showing a portion of the track within the pit;

Figure 4 is a vertical cross section taken on line 4—4 of Figure 2;

Figure 5 is a partial vertical cross section illustrating a gate;

Figure 6 is a plan view with parts in section showing the same;

Figure 7 is a section on line 7—7 of Figure 6.

Like parts are indicated by like characters throughout.

A is a track upon which a locomotive A¹ may be positioned and may move. B is a track which may be parallel to the track A.

The arrangement herewith constitutes a cinder plant that is a receiving and dumping mechanism for receiving cinders and ashes from a locomotive and for raising and dumping the same into a car or other receptacle adapted to carry them away.

C is a receiving pit having walls C¹ and a receiving chute C² which may be formed as a part of the pit or as here shown by the use of additional parts. C³ is a well adapted to receive water or other liquid which may be drawn into the pit to concentrate the same,

and C⁴ is an outlet through which said liquid may escape.

D is a bucket. D¹ is the main hoisting track within the pit and extending upwardly and outwardly. D² is a supporting framework which carries the track and hoisting mechanism and supports the same above the ground. D³ is an auxiliary or guiding track located within the pit communicating with the track D¹ as shown in detail in Figure 3. Throughout the major portion of its length it lies generally parallel with that part of the track D¹ which rests on the bottom of the pit C. D⁴ is a guide track located adjacent the upper end of the track D¹ lying generally parallel to the main portion. D⁵ is a laterally bent extension of the guide track D⁴. It is so bent to cause the bucket D to tip and empty its contents in tipping. D⁶ is an extension from the frame D² to which the upper end of the track D⁴ and the outer end of the laterally bent portion D⁵ are joined. D⁷ is a guide track parallel to the track D⁴ and forming with it a guiding and tipping member. D⁸ is a chute into which the bucket discharges at the upper end of its excursion when tipped. D⁹ is a hoisting cable and D¹⁰ is a hoisting means located at the upper end of the lower or framework D². This hoisting means may be of any suitable type adapted to draw in the cable and to raise the bucket. The details of it form no particular part of the present invention.

E are flanged rollers, one of which is mounted on each side of the bucket. Generally similar rollers E¹ E¹ are located one on each side of the bucket, but these rollers have wider flanges than those of the rollers E. E² is an angle or bail contacting member. Two of these members are mounted upon the bucket, one on each side. When the bucket is in the lower position as shown particularly in Figure 2 the flexible bail is bent about these angle members E².

Fastened to the bucket and preferably to the shaft which carries the rollers E is a flexible bail E³. This bail may be as shown formed of a cable. At its upper end it includes a rigid cross member E⁴ to which the side members of the bail are fastened, and it has mounted preferably adjacent its center a shave E⁵. E⁶ E⁶ are rollers mounted at the outer ends of the shaft E⁴.

The guide track D³ is narrowed at the point where it is joined to the track D¹ and is

provided with cut away portion E^7 . Situated above the guide track D^3 is a second guide track provided with an upward inclined arm E^8 and a lower arm E^9 which is generally parallel to the guide track D^3 . It is provided at its upper end with an upwardly bent portion E^{10} which is generally parallel to the more steeply inclined part of the track D^1 . E^{11} E^{12} are braces mounted about the open pit mouth and forming a support for the upper arms E^8 E^9 .

X is a car standing on the track B and receiving a load, for example, of cinders X^1 .

Although I have shown an operative device, still it will be obvious that many changes might be made in size, shape and arrangement of parts without departing materially from the spirit of my invention; and I wish, therefore, that my showing be taken as in a sense diagrammatic.

In Figures 5 and 6 I have shown a gate adapted to close the receiving pit opening. This gate has been omitted from Figures 1 and 3 in order to avoid confusion and because it is not always used. It may be inserted, however, and usually is inserted in an installation of the sort shown in the main figures.

F is a portion of the pit cover. As here shown it is made of concrete. Located within the pit, preferably, at an incline are tracks G G . These tracks are fastened to the walls C^1 of the pit by means of supports G^1 G^2 .

H is a gate provided with rollers H^1 H^2 which rest upon the tracks G and by means of which the gate is mounted so as to move freely along the track.

I is a shaft supported in bearings I^1 I^2 provided with a gear I^2 having fixed upon it a crank arm I^3 . I^4 is a connecting arm or lever pivotally mounted at one end of the bearing I^5 on the gate H and pivotally connected at its other end to the arm I^3 .

J is a stub shaft mounted in bearings J^1 J^2 carrying at one end a gear J^2 which meshes with the gear I^2 . J^3 is a lever arm mounted on the shaft J extending upwardly through an opening J^4 in the member F .

In Figures 6 and 7 particularly there is illustrated in detail the clutch mechanism which is used where two gates for two receiving buckets are to be operated from the same gate controlling mechanism. One gate alone may be used as shown in Figure 5 and in that case the selective clutch mechanism shown in Figures 6 and 7 is not necessary, although it may be used. Where two gates are used, this clutch mechanism becomes necessary. When the clutch mechanism is used the lever arm I^3 is fastened to a slide collar K which is provided with a notched end K^1 and is mounted for rotation relative to the shaft I . A similar collar L is provided with a notched face L^1 and is mounted on the shaft and pro-

vided with a short lever arm L^2 similar to the arm I^2 which is joined to a connecting rod or arm L^3 .

The shaft I is provided with two separated keys not shown in detail. Mounted on the shaft and provided with key-ways adapted to engage the keys are two clutch members M M^1 . Each of these members has fastened to it a yoke M^2 M^3 respectively, which yokes are joined together by an operating rod M^4 which is slidably supported in bearings M^5 M^6 and provided with a projection M^6 . Each of the members M M^1 has notches on its inner face as shown and they may engage respectively the notches K^1 L^1 .

N is an operating tumbler pivotally supported as shown and provided with projecting jaws N^1 adapted to engage the projection M^6 . N^2 is an operating handle pivotally mounted at N^3 upon the tumbler N for limited movement with relation thereto. N^4 and N^5 are extended contact faces of the tumbler N adapted to be contacted by a portion of the handle N^2 . N^6 is a weight on the handle N^2 .

In operation the clutch mechanism is used so as to throw into or out of operation one or the other gate. As shown in Figure 7 the right hand member L is in mesh with the clutch member M^1 and when the parts are in this position it will be the member L which will rotate with the shaft I and the rod L^3 which will move to open or close the gate to which it is attached.

If it is desired to move the other gate the handle N^2 will be rotated. At first it will move with relation to the tumbler N and cause no movement of the tumbler. When it contacts the face N^4 it can have no further movement with relation to the tumbler N and thereafter raises the tumbler with it for a brief distance, moving the clutch member N^1 out of engagement with the teeth L^1 of the member L and moving the clutch member M into engagement with the teeth K^1 of the member K , to which the lever I^3 is attached. With the parts then in this position, if the lever J^3 did raise, it would move the lever I^3 , the rod K^4 and the gate H .

The use and operation of my invention are as follows:

When the hoist is to be used the bucket is lowered into the pit as shown in Figures 1, 2 and 4. As it moves into the pit, the narrower, that is, the lower rollers of the bucket remain on the main track, passing through or passed the cut-away portion of the guide track D^3 . The upper, that is, the wider rollers are too wide to pass through this cut away portion and as they come to it, they run across the remaining part of the guide track D^3 and are diverted upon the track D^3 thus retaining the bucket in its upright position without tilting it from the position which it occupied when it was supported up-

on the track D^1 alone before it entered the pit.

As the bucket moves downward, the rollers on the rigid cross member of the bail strike the arms E^8 or E^9 and are finally retained at 5 the point of juncture of these arms as shown in Figure 2. When they occupy this position, the cable or yielding portion of the bail is bent as shown over the members E^2 . Thus even if the hoisting cable should break or 10 should be allowed to become loose, the bucket will be retained of itself in an upright position. It cannot jam or slide off the track or become displaced as a result of damage to the hoisting mechanism or as a result of unsatisfactory or incomplete operation of the hoisting mechanism or any part of it. After the 15 bucket has reached the position shown in the bottom of the pit, cinders are deposited into it from a locomotive or from some other 20 source and the main hoisting cable is drawn up by the hoisting apparatus at the top of the tower. The upper rollers move again onto the main track and the rigid cross bail member moves upward until it occupies the 25 position shown in dotted lines in Figure 2. In this position it will be noted that the hoisting effect of the bucket is exerted on the shaft which carries the two lower rollers E .

As the bucket is drawn upward and approaches the upper limit of its excursion, the upper rollers, that is the large flanged rollers E^1 move outward along the track D^5 . Since the hoisting effect is now being exerted through the shaft which carries the rollers E^1 , they do 30 not move outward along the track D^5 but are raised from the track D^1 before they reach the portion D^5 and are brought into contact with the guiding track D^4 and here run upward into the position shown in dotted lines 35 in Figure 1 and the bucket is thus dumped.

The operation of the gate shown in Figures 5 and 6 is as follows: The gate normally will be in the closed position shown in Figure 5. In that position the handle or lever J^8 is in the down position. When it is desired to open the gate, this handle is raised and 40 through the gears the gear I is caused to rotate in a counter clock-wise direction as viewed in Figure 5, the crank arm I^8 moving with it into the dotted line position as shown in Figure 5, and this movement through the connecting member I^4 is transmitted to the gate which is moved out of position in the opening of the pit into the 45 dotted line position whereby the pit opening is left free and available for material.

In Figures 5, 6 and 7, there is shown the gate mentioned in the preceding paragraph. There is also shown a clutch mechanism. 50 This mechanism is not always necessary where only a single gate is used but where two gates are to be used together, controlling the openings to two pits, or to one pit having two openings as is shown in Figures 55 6 and 7, it is preferable to use the clutch.

By this means with one operating handle and one operating mechanism, it is possible to control two gates separately and open them one at a time. I have shown in Figure 7, the operating part L as in engagement 70 with the member M^1 and the gate controlled by the lever L^8 will be operated when the handle J^8 is moved from the position it occupies toward the vertical. To alter this operation the handle M^2 is moved from the 75 position shown in Figure 7 over toward the left in a counter clockwise direction. Thus the member L is disengaged, the member K becomes engaged with the member M and the handle J^8 is then moved from the position which it occupies to the vertical, the operating rod I^4 will be moved and the gate H which it controls will be correspondingly moved. 80

I claim:

1. In combination in a material handling plant, a pit, a bucket adapted to be moved into and from such pit, and hoisting means for moving such bucket, means independent from such hoisting means for limiting the movement of such bucket into said pit, said means including a flexible bail attached directly to such bucket and means for engaging such bail said means including a stop member adapted to engage the bail and to 90 cause the same to bend as the bucket is lowered into the pit, and an additional stop about which such flexible bail is bent when the bucket is lowered within the pit. 95

2. In combination in a material handling plant, a pit, a bucket adapted to be moved into and from such pit, and hoisting means for moving such bucket, means independent from such hoisting means for limiting the movement of such bucket into said pit, said 100 means including a flexible bail attached directly to such bucket having a rigid portion and means for engaging and retaining such rigid portion, said means including a stop member adapted to engage the bail and to 105 cause the same to bend as the bucket is lowered into the pit, and an additional stop about which such flexible bail is bent when the bucket is lowered within the pit. 110

3. In combination in a material handling plant, a pit, a bucket adapted to be moved into and from such pit, and hoisting means for moving such bucket, means independent from such hoisting means for limiting the movement of such bucket into said pit, said 115 means including a flexible bail attached directly to such bucket having a rigid portion, and means for engaging and retaining such rigid portion, and including a generally hook-shaped member adapted to engage the rigid portion of such bail and to cause the bail to bend as the bucket is lowered into the pit, and an additional stop about which such flexible bail is bent when the bucket is 120 lowered within the pit. 125

4. In combination in a material handling plant, a pit, a bucket adapted to be moved into and from such pit, and hoisting means for moving such bucket, means independent 5 from such hoisting means for limiting the movement of such bucket into said pit, said means including a flexible bail on such bucket having a rigid portion and means for engaging and retaining such rigid portion, including a generally hook-shaped track member and wheels on such rigid bail part adapted to contact and be engaged by the track member.
5. In a material handling plant, a pit, a bucket, means for raising and lowering the bucket, such bucket having flexible bail members, one on each side joined by a rigid cross member, said bucket having on each side a pair of rollers, and a pair of guiding and 10 positioning members adapted to receive, guide and finally to limit the downward movement of such rigid bail cross member and to cause the bail to bend as the bucket is lowered into the pit, and a stop about which 15 said bail is bent when the bucket is in the pit.
6. In a material handling plant, a pit, a bucket, means for raising and lowering the bucket, such bucket having flexible bail members, one on each side joined by a rigid cross member, said bucket having on each side a pair of rollers, and a pair of guiding and 20 positioning members adapted to receive, guide and finally to stop the movement of such rigid bail cross member, and positioning members on the sides of such bucket adjacent the upper 25 roller, such flexible bail members adapted to bend about such positioning members when the bucket is in the pit.
7. In a material handling plant, a pit, a track running in such pit, a bucket running on said track, means for raising and lowering the bucket, such bucket having flexible bail members one on each side joined by a rigid 30 cross member, such cross member carrying at its outer end rollers, said bucket having on each side a pair of rollers, and a pair of guiding and positioning members adapted to receive, guide and finally to stop the movement 35 of such rigid bail cross member.
8. In a material handling plant, a pit, a track running in such pit, a bucket running on said track, means for raising and lowering the bucket, such bucket having flexible bail members one on each side joined by a rigid 40 cross member, such cross member carrying at its outer end rollers, said bucket having on each side a pair of rollers, there being a guide track within the pit adapted to receive the bucket rollers, and a pair of guiding and positioning members adapted to receive, guide and finally to stop the movement 45 of such rigid bail cross member, and positioning members on the sides of such bucket adjacent the upper roller, such flexible bail members adapted to 50 bend about such positioning members when the bucket is in the pit.
9. In a material handling plant, a pit, a bucket adapted to be moved into said pit, means for moving such bucket, and guide means within such pit, a corresponding projecting member on such bucket adapted to move along such guide members to guide and support the bucket and to retain the same in the upright position, and means for limiting 55 the movement of the bucket into the pit, such means including a bail member on the bucket, and a track partially within the pit, to receive such members and guide the same and finally to stop their movement.
10. In a material handling plant, a pit, a bucket adapted to be moved into said pit, means for moving such bucket, and guide means within such pit, a corresponding projecting member on such bucket adapted to 60 move along such guide members to guide and support the bucket and to retain the same in the upright position, and means for limiting the movement of the bucket into the pit, such means including a bail member on the bucket and track partially within the pit, to receive such members and guide the same and finally to stop their movement, there being rollers on such bail members adapted to be guided and finally to be stopped by such last mentioned track members.
11. In combination in a material handling plant, a pit, a pair of generally parallel sets of tracks within such pit, a single main track extending upwardly out of such pit at an angle to such first mentioned tracks, a bucket, means for moving the bucket into and out of the pit, rollers on such bucket adapted to move on such tracks, all of such rollers adapted to move on the main track, the tracks within the pit being so formed that some of the rollers move on one set of tracks and the others on the other set, a guiding track at the upper end of the main track, the main track being laterally bent, means for causing some of the rollers to run along such laterally bent portion and for causing them to run along the guide track whereby the bucket is dumped, and means for limiting the movement of the bucket into the pit, said means including a bail member and a bail retaining, guide and stop member located within the pit.
12. In combination in a material handling plant, a pit, a pair of generally parallel sets of tracks within such pit, a single main track 120 extending upwardly out of such pit at an angle to such first mentioned tracks, a bucket, means for moving the bucket into and out of the pit, rollers on such bucket adapted to move on such tracks, all of such rollers adapted to move on the main track, the tracks within the pit being so formed that some of the rollers move on one set of tracks and others on the other set, a guiding track at the upper end of the main track, the main track being laterally bent, means for causing some of the rollers to run along such laterally bent portion and for causing them to run along the guide track whereby the bucket is dumped, and means for limiting the movement of the bucket into the pit, said means including a bail member and a bail retaining, guide and stop member located within the pit.

ally bent, means for causing some of the rollers to run along such laterally bent portion and for causing them to run along the guide track whereby the bucket is dumped, 5 and means for limiting the movement of the bucket into the pit, said means including a bail member and a bail retaining and guide and stop member located within the pit, such bail member provided with a roller, such stop member including a track along which the 10 roller runs, such track being so shaped as to stop the roller.

Signed at Chicago, county of Cook, and State of Illinois, this 3rd day of September, 1926.

CLYDE P. ROSS.
